Inventor:

Ruben P. Buttles.

UNITED STATES PATENT OFFICE.

REUBEN P. BUTTLES, OF MANSFIELD, PENNSYLVANIA.

IMPROVEMENT IN COMBINED TOWEL-RACKS AND WASH-STANDS.

Specification forming part of Letters Patent No. **158,401**, dated January 5, 1875; application filed May 23, 1874.

To all whom it may concern:

Be it known that I, REUBEN P. BUTTLES, of Mansfield, in the county of Tioga and State of Pennsylvania, have invented new and useful Improvements in Revolving Wire Stands and Towel-Racks; and I do hereby declare that the following is a full, clear, and exact description of the construction and operation of the same, reference being had to the annexed drawings making a part of this specification, and to the letters and figures of reference marked thereon.

Figure 1 is a side view of my improved wire stand. Fig. 2 is a view of the lower end of one of the supporting-legs. Fig. 3 is a sectional view of the connection of the base with the central portion. Fig. 4 is a view of one of the rack-bars.

The object of my invention is to construct a light portable revolving wire stand, the parts of which can be readily detached for transportation and quickly put together, and which is provided with removable rack-bars and means for securing the base portion in position, as hereinafter more fully described.

In the accompanying drawings, *a* represents a collar or ring, provided with perforations on its upper face for the reception of the wires *b b*, any number of which can be employed. *c* is a wire wound around the lower ends of the wires *b* to confine them together. At the upper end of the binding-wire *c* the wires *b b* diverge in pairs, each pair being separated for a short distance, then wound around each other, so as to form ovals or loops *d d*, with intermediate wire-twisted connections *e e*. The upper ends of each pair of wires are wound around the circumference of a larger concentric circle, *c'*.

It is obvious that the lower ends of the wires *b b* may be attached to the collar *a* by any suitable fastening, though I prefer the fastening above described.

The pairs of wires *b b* above the binding-wires *c* may be given any desired form. The

letter *h* represents a collar or ring, the lower face of which is provided with perforations for the reception of a series of wires, *i i*, introduced and fastened therein, the collar *h* being directly under, and being of the same diameter as, the collar *a*. The wires *i i* immediately under the collar *h* are confined and bound together for a short distance by the wire *k*, at the lower end of which the wires *i i* are made to diverge in pairs, each pair having loops *l* and twisted portions *n*; when the wires of each pair are bent at a very obtuse angle with each other, and one of the wires is bent downward so as to form a hook, *p*, to catch into the floor, the other wire, *o*, of the pair being provided with an eye, *p'*, resting on the floor. The letter *r*, in Fig. 3, represents a central connecting-pin passing down between the rings *a h*, between the wires *b b* and *i i*, and down through the base, its lower end being sharpened so as to engage with the floor. *s*, in Fig. 4, is a rack-bar, as seen at *t u*, to adapt it to be readily hooked over the circle *c'*, and its interior concentric circle.

By this construction it will be seen that the rack-bar may be applied at any point of the circle *c'*, and can be moved around said circle, if desired, and they may be maintained in a horizontal position to support towels or clothes, and when not in use they may be made to occupy a vertical position, as seen in Fig. 1. A wash-basin may be inserted in the inner circle.

What I claim as my invention, and desire to secure by Letters Patent, is—

The collar *a*, having wires *b b*, terminating at their upper ends in concentric circles, in combination with the collar *h*, provided with wires *i i*, terminating at their lower ends in hooks *p* and eyes *p'*, and central pin *r*, substantially as and for the purpose set forth.

REUBEN P. BUTTLES.

Witnesses:

P. V. CLARK,
Mrs. P. V. CLARK.
